UNITED STATES PATENT OFFICE.

GEORGES HALTER, OF PARIS, FRANCE.

APPARATUS FOR BINDING PACKING CASES AND SIMILAR OBJECTS BY MEANS OF HOOPS.

Application filed June 11, 1928, Serial No. 284,564, and in France May 14, 1927.

It is the usual practice, in order to strengthen packing cases or to render them free from the possibility of damage or for both purposes, to bind them with steel wires or hoop bands and to secure said steel wires or metallic bands or hoops by any suitable means such as resistant metal clamps or the like.

In the case of binding with steel wire, there are various automatic apparatus which allow of carrying out the various operations at one time. For binding with hoop-iron on the contrary, it has not hitherto been possible to produce an apparatus which will allow of carrying out the various operations necessary. Thus such operations usually are carried out by means of three independent mechanisms; a tensioning apparatus by means of which the necessary tension is given to the hoop, an assembling apparatus which allows of joining the two ends of the hoop, and shears for cutting the band of hoop-iron after such assembly has been effected.

The present invention relates to an apparatus for stretching a metal hoop and comprises a tightening roll, means for applying one of the ends of the hoop to one of the peripheral points of this roll, means for applying to the roll at a different point on its periphery, a part of the same band forming the other end of the hoop to be formed, and means for turning the roll about its axis in one direction only, so as to impart, by this rotational movement of the roll, displacements to the two ends of the band in different directions and thus to stretch or tighten the same on the articles to be bound.

The present invention also relates to an apparatus for carrying out all the operations required in binding, i. e., tightening the band, assembling, with or without clamps, the free end of this band over the other part of the band fed towards it, and cutting said band. Further all these operations are carried out by means of a single operating lever. As the attendant does not release the lever during these operations he can consequently rapidly bind cases and bales of all types.

The accompanying diagrammatic drawings are given by way of example and are not to be taken as in any way limiting the scope of the present invention.

Figure 1 is a view in elevation showing the method of using the apparatus.

Figures 2 to 4 show a clamp which can be used with the apparatus shown in Figure 1, Figure 2 being a developed plan view, Figure 3 a plan view showing the same clamp in the form in which it is introduced into the apparatus and Figure 4 an end elevation showing the same clamp in the form shown in Figure 3.

Figure 5 is a plan view showing the clamp illustrated in the preceding figures secured to the hoop after finishing these operations.

Figure 6 is a transverse section of the hoop across the point where it is secured.

Figure 7 is an elevation of the apparatus forming the object of the present invention.

Figure 8 is a vertical axial section through the same apparatus.

Figure 9 is a horizontal section along the line 9—9 in Figure 8.

Figure 10 is a transverse section along the line 10—10 in Figure 8.

Figure 11 is a detail view of the rack lever.

Figure 12 is an end elevation of the apparatus from the side of the tensioning roll.

The same reference numerals indicate the same elements in the various figures.

In Figure 1 the binding machine A is shown above a bale a around which is a metal band b from a drum c. The free end d of this band is engaged by the machine A and the portion e also passes through this apparatus after having passed around the bale a.

By means of the machine A which has just been described, the band passed around the bale is first tensioned and then the two ends d and e are brought together by means of a clamp f, the band remaining stretched, and finally the portion e is cut and separated from the drum c.

The clamps used for this union of the two ends of the band consist of a metal plate which is preferably previously pierced by a hole g. Figure 2. The sides h, i of this plate are bent into the form of a U (Figures 3 and 4). A clamp of this shape is introduced into the machine A which, when the band is stretched around a bale, forces the sides h and i against the walls d and e of this hoop Figures 5 and 6, widens the opening g of the clamp, perforates the ends d and e of the hoop and at the same time seals the ends d and e together and with the clamp f Figure 6, the sides of the opening g of the clamp being forced into the openings provided in the ends d and e and thus preventing any slipping of the end d relative

to the end *e*. As soon as this has been done, the end *e* is cut off and separated from the drum *c* by means of the same apparatus.

The binding is then completed and the apparatus A can be withdrawn.

The invention is of course not limited to an apparatus A adapted solely for use in combination with clamps of the shape shown in Figures 2 to 6. Clamps of other shapes 10 or type may also be used and the apparatus can be adapted to the shape selected. The apparatus can also be simplified in order to produce hoops, the two ends of which are to be superimposed without a clamp by any 15 suitable means. Similarly hoops previously cut to the correct length can be used and the cutting mechanism can be eliminated.

The following description refers to a complete apparatus which allows of carrying out 20 all the operations described above. This apparatus comprises a base on which are mounted:—

A tensioning apparatus which allows of stretching the hoop over the object in question as tightly as necessary, 25

A mechanism for closing a clamp placed over the tensioned hoop,

A mechanism for binding the ends of the hoop together,

30 An apparatus for cutting the hoop, and preferably, a single lever controlling all such mechanisms.

In the example shown in the drawings, the mechanisms are all mounted on a base 1 provided with a handle 2 adapted to facilitate the operation of the machine.

The single lever 3 is connected with the four mechanisms mentioned, so that a to and fro motion imparted to the lever through a 40 given angle causes the functioning of the tensioning apparatus alone, the other mechanisms remaining out of action, whilst displacement of the same lever through a second angle forms the clamp, and displacement through a third angle brings the ends of the hoop together and cuts the end of the hoop connected to the feed drum.

Tensioning mechanism.

50 The tensioning mechanism comprises a roll 4, Figure 12, arranged at one end of a spindle 5 which carries at the other end a ratchet 6 actuated by a pawl 7 mounted on the lever 3. The pawl is held permanently against the ratchet 6 by means of a spring 8. The lever 3 rotates on a sleeve 9 carried by an element 10 mounted on the spindle 5 and provided with a sector 11 acting as guide for the lever.

60 A pawl 12 bearing against the ratchet 6 under the action of a spring 13 anchored in the base 1 of the machine prevents any return movement of the ratchet 6.

The element 10 is itself movable about a spindle 14 mounted on the base 1, Figure 7.

A spring 15 tends to keep it away from the base (Figure 8). It is provided with an abutment 16 rendering it integral with the actuating lever 3, as soon as the lever brings the two ends of the band together.

The roll 4 is positioned between two bosses 17 and 18 formed on arms 19 and 20 of the base 1.

As shown in the drawings these bosses 17 and 18 are so positioned that on insertion 75 of the band ends as hereinafter described and swinging of the roll into tensioning position, the bosses hold the band ends against portions of the roll substantially diametrically opposite to each other.

The lever 3 is provided with a V-shaped boss 21 adapted to actuate the other mechanisms and also that which is about to be described.

Mechanism for closing the clamp over the hoop.

The clamp closing mechanism Figures 8, 9 and 10 comprises two lateral levers or jaws 22 Figure 10 articulated on spindles 23 90 mounted on the base 1. The lower portion of each of the jaws is provided with a hook 24 and notch 25. On closing the jaws 22, the hooks 24 force the two arms *h* and *i* of the clamp against the two ends *d* and *e* of the band *b* and these arms thus turned are held in the two notches 25 in these jaws.

Each of the levers 22 is also provided with an inclined ramp 26 arranged opposite a similar ramp 27 on one of the arms 28 of a bifurcate member 29, mounted on a sleeve 30 enclosing a spring 31 and located opposite an abutment 32 provided on the base 1. This sleeve is also provided with an abutment 33 mounted opposite the boss 21 on the lever 3. 100

105 Springs 34, mounted between the jaws 22 and the base 1, keep the jaws open under normal conditions.

Under these conditions, when a thrust is brought to bear on the boss 33 by means of the 110 levers 3 through the boss 21, the ends 27 of the arms of the bifurcate member 29 cause the jaws 22 to close, and consequently close the arms of the clamp over the ends of the hoop band.

115 The bifurcate member 29 exerts a thrust on the jaws normal to their plane of movement, which thrust is preferably taken up by ball bearings 35 which can be inserted between the jaws 22 and abutments 36, provided on the sides of the base 1.

Mechanism for uniting the ends of the hoop.

The uniting mechanism Figures 8, 9 and 10 comprises a punch 37 secured to a stamp 125 38 movable about an axis 39 and actuated by two articulated levers 40 and 41, operated by a rod 42, articulated to the axle 43 common to the two levers. This rod is co-axial with the sleeve 30 and acts as a guide for the lat- 130

ter. It is provided with a shoulder 44 abutting on one side against the boss of the sleeve 30 and on the other against the spring 45, wound round the rod 42 between this shoulder 44 and the face of the abutment 32 on the base 1.

One of the axes 46 and 47 of the levers can be mounted on an adjustable eccentric 48 in order to allow of exact adjustment of the 10 height of the punch 37.

Mechanism for cutting the hoop.

The stamp 38 is provided with striker 49, arranged above one blade of the shears 50 15 carried by the jaws 22 of the mechanism for closing the clamp, and actuated so as to bite into the end *e* of the hoop on completion of the punching operation so as to leave the end *d* intact. The force of the blow, and the position of the eccentric 48, are to be so regulated that the blade 50 will just shear band end *e* without penetrating into band end *d*. It is not essential that the shear of band end *e* be absolutely complete as the fact that portion *e* of the band is already under tension tends to tear the band when partially severed. Furthermore, as hereinafter set forth, the swinging away of the tensioning roll tends to pull on band *e* where it is engaged 25 with the same, thus to tear band *e* at the portion where it has been substantially severed by blade 50, if the tension on the band has not completed the severance.

The blade 50 of the shears slides in a guide 30 formed in the lever 2 and is held in place by means of the key 51.

This blade 51 cooperates with a shoulder 51' integral with the blade 51 acting as an anvil during the cutting of the hoop.

40 Finally rollers 52, 53 which guide the hoop are inserted in the base of the apparatus, Figure 8.

Operation.

45 The apparatus held by the handle 2 is placed in the correct position on the article to be bound, for example a packing case, at the point where the binding is to be formed, Figure 1, the actuating lever 3 being left free. The jaws 22 are then held open by springs 34. The spring 45 maintains the punch 37 in its raised position and leaves the shears 50 free.

The end *e* of the hoop *b* carried by the reel 55 *c* is passed over the roll 4 between the latter and the upper boss 17 of the base 1. For this purpose this roll carried by the members 10, 11 is held away from the base 1 by the springs 15 until this element just abuts against the

60 base 1, Figure 11, at the point 54, and this end *e* of the hoop is passed below the rollers 52 and 53, and then below the jaws 22 (during this adjustment the operator bears slightly on the handle 2). The band *b* is then 65 wound round the case *a* and the end *d* is

passed below the apparatus under the roll 4, between the latter and the lower boss 18, and then again below the jaws 22 until slightly beyond the same (Figure 1).

At this moment, the operating lever 3 is 70 moved in the direction of the arrow in Figure 1. The friction of the lever 3 on the element 10, 11 wedges the roll between the two ends *d* and *e* which then bear against the bosses 17 and 18, so that by giving the lever 75 3 to and fro movement through the angle α the pawl 7 acts on the ratchet 6, turns the roll and causes the two ends *d* and *e* to move in opposite directions thus tensioning the 80 hoop about the object *a*. The pawl 12 prevents the ratchet from slipping back. As soon as the tension has reached a sufficient value, the lever 3 is returned to its position of rest and a clamp *f*, Figures 3 and 4, is 85 passed between the jaws 22 up to the cutter 50.

By displacing the lever 3 through the angle β toward the handle 2, the boss 21 being then in contact with the boss 33, the element 28, 29, 30 slides between the jaws 22, closes the latter and consequently forces the arms *h* and *i* 90 of the clamp against the hoop; then continuing the movement of the lever 3, so as to move it through an angle α , the connecting rod 42 actuates the levers 40 and 41, and the stamp 38 and the punch 37 are lowered and punch 95 the two ends *d* and *e*, uniting the latter together and with the clamp *f*. The hammer 49 then strikes the blade 50 which cuts the band to the rear of *e* only, the band *d* remaining intact. The sealing pressure is maintained 100 by the lower portions of the levers, and the cutting pressure by the shoulder 51'.

It is to be noted that, shortly before reaching the end of its movement, the lever 3 contacts with the abutment 16, becomes integral 105 with the element 11, and its short arm is reduced to the distance 55 separating the axis 14 from the boss 33, so that this lever transmits a powerful blow at the moment of cutting the band. At the same time the roll 4 110 disengages from the band *d* and the pawl 12, and due to its biting into the upper band, tends, as it swings away, to carry the upper band with it thereby tearing the band at the portion substantially cut through by the blade 115 50, in case the blade has not entirely severed the tensioned upper band, as set forth above.

In order to remove the apparatus it is sufficient, after having pushed the lever sufficiently back, to lift the punching end of the 120 device off of the band joint, and then (as the tensioning roll is already disengaged) to push the entire apparatus sideways to slide arm 20 from beneath the band *d*.

In the apparatus described above and 125 shown in the accompanying drawings, it has been supposed that a single lever 3 actuates all the mechanisms carrying out the various operations, but it should also be understood that, without going beyond the scope of the 130

present invention, an apparatus can also be constructed which allows of carrying out the same operations by means of a plurality of separate levers, each of which is adapted to 5 carry out one or more of these operations, which levers are actuated successively in desired sequence.

I declare that what I claim is:—

1. In an apparatus for tensioning a metal binding hoop the combination of two convergent abutments arranged on the base of the apparatus, a roll for tensioning the band arranged between said convergent abutments, a free passage for the end of the band between the roll and each of said abutments, means for altering the distance between the roll and each of these abutments, in order to tension each end of the band between the roll and the corresponding abutments, and means 15 for turning the roll about its axis in one direction only so as to impart opposite movements to the two ends of the band and thus to tension said band around the object to be bound.
2. In an apparatus for tensioning a metal binding hoop the combination of two convergent abutments arranged on the base of the apparatus, a support provided with a pivot mounted on said base, a spindle carried by said support and carrying a roll for tensioning the band, said roll being positioned 25 by the said convergent abutments, a free space between said roll and each of the abutments, in order to allow one end of the band to pass, and a pawl actuated lever, mounted on the axis of the roll, a ratchet wheel integral with the roll, said lever adapted to turn said support on the base of the apparatus in order to introduce said roll between the ends of the band and to place each end between the roll 30 and the corresponding abutment of the base and consequently to turn the roll around its axis in one direction only in order to impart displacements in opposite directions to the two opposite ends of the band and to tension 35 the latter around the object to be bound.
3. In an apparatus for fastening a metal binding hoop, the combination of two convergent abutments arranged on the base of the apparatus, a support provided with a pivot mounted on said base, a spindle carried by said support and carrying a tensioning roll for tensioning the band, said roll being positioned by the said convergent abutments, a free space between said roll and each of the 40 abutments, in order to allow one end of the band to pass, and a pawl-actuated lever mounted on the axis of the roll, a ratchet wheel integral with the roll, said lever adapted to turn said support on the base of the apparatus in order to introduce the roll between the ends of the band and to place each end between the roll and the corresponding abutment of the base and consequently to turn the roll around its axis in one direction only and means for binding together the 45

two opposite ends of the band thus tensioned about the object to be bound.

4. In an apparatus for fastening a metal binding hoop, the combination of two convergent abutments arranged on the base of the apparatus, a support provided with a pivot mounted on said base, a spindle carried by said support and carrying a roll for tensioning the band, said roll being positioned by the said convergent abutment, a free space 50 between said roll and each of the abutments, in order to allow one end of the band to pass, and a pawl-actuated lever mounted on the axis of the roll, a ratchet wheel integral with the roll, said lever being adapted to turn said support on the base of the apparatus in order to introduce the roll between the ends of the band and to place each end between the roll and the corresponding abutment of the base and consequently to turn the roll 55 around its axis in one direction only, means for cutting the end of the hoop adjacent the band of metal of which the hoop is formed, and means for bringing together the two opposite ends of the band thus tensioned about 60 the object to be bound.

5. In an apparatus for forming from a band a tensioned hoop about an object to be bound, in combination, a tensioning roll having a toothed periphery, means for applying one end of the band to a point on the toothed periphery of said roll, means for applying the part of the same band adapted to form the other end of the hoop to another point on the periphery of said roll, said applying 65 means being so related to the roll as to bring each of the band parts forcibly against the teeth of the roll on opposite sides of the axis thereof, and means for turning the roll about its axis in one direction only in order by this 70 rotational movement of the roll to impart displacements in opposite directions to the two ends of the band and to tension the same about the object to be bound.

6. In an apparatus for forming from a band a tensioned hoop about an object to be bound, in combination, a tensioning roll having a roughened periphery, means for applying one end of the band to a point on the roughened periphery of said roll, means for applying the part of the same band adapted to form the other end of the hoop to another point on the periphery of said roll, said applying means being so related to the roll as to bring each of the band parts forcibly 75 against the teeth of the roll on opposite sides of the axis thereof, means for turning the roll about its axis in one direction only, and means for preventing any rotation of the roll in the opposite direction in order by this rotational movement of the roll to impart displacements in opposite directions to the two ends of the band and to tension the same about the object to be bound.

7. In a device of the class described, in 80

- combination, a frame provided with a pair of abutments, an arm pivotally carried by said frame, a toothed roll rotatably carried by said arm in position to be swung between said 5 abutments to simultaneously engage band ends inserted respectively between said roll and each of said abutments, means for effecting such swinging motion of said roll, and means for rotating said roll in one direction 10 only for displacing said band ends in opposite directions.
8. In a device of the class described, in combination, a pair of abutment members, one of said abutment members being arranged 15 at a wedging angle with respect to the other, said abutment members adapted each to receive in abutting relation a portion of a band to be formed into a baling hoop, a toothed roll adapted to swing between the two band 20 portions to force them against their respective abutments, and to be wedged therebetween, and means for causing rotation of said roll in one direction only to displace said band portions in opposite directions.
- 25 9. In an apparatus for forming a hoop from a metal band, in combination, a frame provided with a base plate and an abutment lying thereabove and spaced therefrom, a toothed roll indirectly carried by said frame and positionable between said base plate and said abutment, said base plate and roll being adapted to receive therebetween a portion of the metal band to be formed into a hoop, and said abutment and roll being adapted to 30 receive therebetween the portion of the metal band lying at the other extremity of the hoop forming portion, guiding members carried by said frame for positioning said two band portions in overlying relation, means carried 35 by said frame and extending laterally on opposite sides of said overlying portions, and adapted to be moved to hold said overlying portions for fastening, means carried by said frame including a fastening member positioned above said overlying portions and a cutting member positioned to operate on said 40 second mentioned hoop portion, and a single operating means adapted to be operated to successively position said roll, rotate the same for displacing said band ends in opposite directions to tension the hoop, move said laterally disposed members to holding position, and operate said fastening and cutting means.
- 45 10. In an apparatus for forming a hoop from a metal band, in combination, a frame provided with a base plate and an abutment lying thereabove and spaced therefrom, a toothed roll indirectly carried by said frame and positionable between said base plate and said abutment, said base plate and roll being adapted to receive therebetween a portion of the metal band to be formed into a hoop, and said abutment and roll being adapted to 50 receive therebetween the portion of the metal band lying at the other extremity of the hoop forming portion, guiding members carried by said frame for positioning said two band portions in overlying relation, means carried by said frame including a fastening member positioned above said overlying portions and a cutting member positioned to operate on said second mentioned hoop portion, and a single operating means adapted to be operated to successively position said roll, rotate the same for displacing said band ends in opposite directions to tension the hoop, move said laterally disposed members to holding position, and operate said fastening and cutting means and
- 55 11. In a combined band tightening, sealing, and cutting means, a frame, a tensioning roll having a roughened periphery and indirectly carried by said frame, a pair of abutments carried by said frame and cooperating with the periphery of said roll to hold two band ends therewith for displacement thereby, sealing and cutting means carried by said frame in position to operate for sealing together said band ends and for cutting off the overlying portion of one of the same, and operating means correlated with said tensioning roll and sealing and cutting means for effecting cooperation between said roll and said abutments, for rotating said roll to effect displacement of said band ends in opposite directions, and for effecting operation of said sealing 60 and cutting means, substantially as described.
- 65 70 75 80 85 90 95 100
- In testimony whereof, I have signed my name to this specification.
- GEORGES HALTER.
